UNITED STATES PATENT OFFICE.

JOHN McGRATH, OF NEW YORK, N. Y.

HEAD-REST FOR COFFINS.

SPECIFICATION forming part of Letters Patent No. 378,207, dated February 21, 1888.

Application filed August 8, 1887. Serial No. 246,427. (No model.)

To all whom it may concern:

Be it known that I, JOHN McGRATH, of the city, county, and State of New York, have invented a new and Improved Corpse Head-
5 Rest, of which the following is a full, clear, and exact description.

My invention relates to an improved head-rest for a corpse, and has for its object to provide an attachment to an ice-box, embalming-board, or dissecting-table, whereby the head of a corpse may be inclined, as desired, and the mouth be held closed.

The invention consists in the construction and combination of the several parts, as will
15 be hereinafter fully set forth and pointed out in the claims.

Reference is to be had to the accompanying drawings, forming a part of this specification, in which similar letters of reference indicate
20 corresponding parts in both the figures.

Figure 1 is a perspective view of the device, and Fig. 2 is a side elevation illustrating its application.

In carrying out the invention the rectangular base A is provided upon its upper face with a series of transverse integral projections, a, whereby a substantially-racked surface is produced. Centrally to the base at one end a horizontal neck, B, is attached or cast integral
25 therewith, near the end of which neck one end of a curved plate, C, is attached, the other end of the plate being adapted to project over and beyond the base.

The plate C is formed longitudinally with a double curve, whereby the said plate is adapted to the contour of the neck and rear portion of the head, as illustrated in Fig. 2. By reason of this double curve that portion of the plate adapted to receive the head when not supported
35 above the base will rest thereon. Thus the back of the head and shoulders will be in essentially the same plane.

Near the free end of the main plate C, and transversely of the same, a concave or segmental plate, D, of spring metal is rigidly secured, which concave or segmental plate is adapted to embrace the head of the subject at or above the ears, and to the ends of the transverse concave plate, upon the outer side, a strap, H, of any suitable material—such as webbing or
45 rubber—is detachably connected in any ap-

proved manner, preferably by buttoning the strap at its ends over lugs b integral with the plate. The strap is adapted to pass over the chin of the subject and keep the mouth in a closed position, and to suit various subjects a series of button-holes may be provided each
55 end of the strap.

To the main plate C, beneath the transverse concave plate D, a bar, d, is secured having its ends d' turned upward at right angles to engage the under surface of the transverse plate D, and provided with a recess, d'', in its upper edge, as shown in Fig. 1, and in said recess one end of a supporting-frame, E, is pivoted, the other end being adapted to engage the racked surface of the base. The said supporting-frame consists of two parallel bars, e, united by transverse rods e', and the pivotal connection with the bar d is effected through lugs cast integral with the inner side of the bars e at the top and at right angles thereto.

In operation, the device may be attached by screws or otherwise to an embalming-board or ice-box, and the head of the subject is laid thereon, as shown in Fig. 2, the strap passing over the chin, and the head may be raised at any inclination by raising the main plate C and allowing the ends of the supporting-frame to engage a suitable projection on the base; or the head may be laid in a plane with the body by throwing the ends of the supporting-frame off the base and permitting the side bars, e, to rest upon said base.

When used in connection with a dissecting-table in adjusting the head, as the device is not attached to the marble slab, one hand is employed to hold the device steady and the other to manipulate the supporting-frame, as indicated in Fig. 2.

The device may also be used with good effect in connection with operating-tables, in which event the strap may or may not be used, as desired.

Having thus fully described my invention, I claim as new and desire to secure by Letters Patent—

1. A head-rest for a corpse, consisting of a base, a longitudinal curved plate attached to said base adapted to the contour of the neck and head, a concave plate transversely attached to said curved plate, and means for vertically

adjusting the combined plates over the base, substantially as set forth.

2. A head-rest for a corpse, consisting of a base, a longitudinal plate attached to said base 5 curved to conform to the contour of the neck and head, a concave plate secured transversely to said longitudinal plate, a detachable chin-strap attached to said concave plate, and means for adjusting the combined plates above the base, substantially as and for the purpose herein set forth.

3. A head-rest for a corpse, consisting of a base having a racked upper surface, a longi-

tudinal plate attached to said base curved to conform to the contour of the neck and head, 15 a concave spring-plate secured transversely to the longitudinal plate, provided with a detachable chin-strap, and a frame pivoted beneath the longitudinal plate, adapted to engage the racked surface of the base, substantially as and 20 for the purposes herein set forth.

JOHN McGRATH.
